UNITED STATES PATENT OFFICE.

MATTHEW H. LOUGHRISE, OF NEW YORK, N. Y.

RAILWAY SIGNAL SYSTEM AND APPARATUS.

1,215,173.

Specification of Letters Patent. Patented Feb. 6, 1917.

Application filed March 5, 1913. Serial No. 752,222.

To all whom it may concern:

Be it known that I, MATTHEW H. LOUGHRISE, born in county Antrim, Ireland, naturalized a citizen of the United States, and a resident of the city of New York, borough of the Bronx, in the county of and State of New York, have invented certain new and useful Improvements in Railway Signal Systems and Apparatus, of which the following is a specification, reference being had therein to the accompanying drawings, forming a part thereof.

My invention relates generally to a railway signal system whereby a visual signal is operated in the locomotive cab with reference to the characteristics of the track, and to which a means may be added of controlling the motive power and the braking power of the locomotive. And my invention particularly relates to a selective means of operating the said cab signal and controlling means in response to various characteristics of the track.

Generally stated, the objects of my invention are to provide a means of producing a number of different indications in the locomotive cab, in response to predetermined combinations of a selector, having reference to the characteristics of the track, and a means of producing these various indications in a safe and reliable manner that cannot be produced accidentally.

My invention comprises various features, which will appear clearly in the light of the following complete specification, as I describe that particular embodiment of my invention illustrated in the accompanying drawings in which Figure 1 is an elevation of the device on the locomotive, known as the selector, which engages a device placed adjacent to the track. Fig. 2 is a side-elevation of Fig. 1, with the cylinder shown in cross section. Fig. 3 is cross section on the air channel of the valves of the selector in one position, and Fig. 4 is a cross section on the air channel, with another combination of these valves. Fig. 5 shows the track device, which I will call a ramp, for one combination, and Fig. 6 shows a ramp for another combination; these ramps being shown in perspective. Fig. 7 shows the indicator in the locomotive cab and a means of controlling the throttle and air-brake, one of the cylinders being shown in cross section. Fig. 8 shows an application of the system to a railroad track where the char-

acteristics are fixed; the case illustrated including a drawbridge where a slow speed is required in passing the draw, and Fig. 9 shows an application where the characteristics of the track may change; that shown being a switch to the side track where a slow speed is required, a high speed being permissible for movements on the straight track.

My invention consists of an iron frame 2 secured to the locomotive 1 by bolts 3. This frame contains the three vertical rods 4, 5 and 6 which have a free vertical motion limited by the set screws 4^a, 5^a and 6^a engaging the slots 4^d, 5^d and 6^d, which also prevents the rods from turning in the frame. These rods are kept in tension downward by the springs 4^b, 5^b and 6^b. The upper end of frame 2 supports the valve disks 14 and 16 moving on the shaft 17 between the cylinders 18—19—20. Said frame also supports a tank 12. In said tank air is compressed by piston 15 at the top of the plunger 5. An outlet pipe 13 connects the tank 12 and cylinder 18. The lift of rod 4 produces a rotary motion of valve disks 14 through the detent 4^c pivoted at 4^e and held in position by spring 4^d engaging the ratchet teeth with which disks are provided at their periphery. The rotary motion of ratchet wheel 16 is secured in a similar manner by the movement of rod 6. The coil springs 14^b—16^b tend to restore said valve disks to their normal position, determined by the pins 14^c—16^c and the stops 2^a as shown in Fig. 1 of the drawings. To hold said disks from retracting ratchets 14^a—16^a are provided. Said ratchets 14^a—16^a are engaged by dogs 7^a—8^a respectively; these dogs are operated by levers 7—8, which are pivoted in the ends 4^e—6^e of the rods 4—6 and move said dogs to engage ratchets 14^a—16^a when said rods 4 and 6 lift. The lever 8, Fig. 2, has a bearing 8^d and the dog 8^a has a bearing 8^e. The two members are mounted separately and operatively connected by a coil spring 8^c permitting the operation of the ratchet 16^a when the disk 16 is rotated. It will be noted that there is a dog in engagement with the opposite disk during the period when either of the rods 4 and 6 are lifted and that when restored to the normal position they permit the disks 14—16 to retract to their normal positions.

Adjacent to the track rail a ramp such as shown in Fig. 5 is supported on the ties 28,

The ramp is designed to lift the rod 5, thereby compressing air in the cylinder 12. The ramp is also designed to produce a predetermined number of lifts of rods 4 and 6. A corresponding number of progressions of disks 14-16 results. The ramp, as shown in Fig. 5, consists of three ridges 25, 26 and 27, on different horizontal planes to engage the rods 6, 5 and 4. The rollers 4^a, 5^a and 6^a, reduce the friction at the point of contact. The ridge 26 is raised to guide the rods 4 and 6. When the rods engage the ramp, they are lifted up by the incline 25^a, 26^a and 27^a. On ridge 27, depressions 27^b and 27^c are provided, which permits rod 6 to drop when passing over them, and ridge 25 has a depression 25^a which permits rod 6 to drop when passing over it. The depressions may be, of course, increased in length to afford sufficient time to operate on high speed trains. It will be noted that the depressions on ridge 27 and those on ridge 25 are not opposite and therefore rods 4 and 6 are not both depressed at the same time. Thus the depressions in the ridges 25 and 27 cause a corresponding number of steps of the disks 16 and 14 to be thereafter retained by the dog with which it is associated.

The combination of steps caused by the ramp shown in Fig. 5, may be arranged to arrange the air ducts in the valve disks and cylinders 18, 19 and 20, as shown in Fig. 3 of the drawings. This provides a free passage from the pipe 13 to the pipe 21 through ducts 18^a, 14^a, 19^a, 16^a and 20^a.

The ramp in Fig. 6 has depressions 25^a and 25^b in ridge 25 and depression 27^a in ridge 27, these depressions being alternately spaced. This combination arranges the air ducts as shown in Fig. 4, through the ducts 18^a, 14^a, 19^a, 16^a and 20^a, to provide a free way from pipe 13 to pipe 22. Where the various ducts join they are expanded to provide for any irregularity in alignment.

Attention is here called to an important element in my invention which requires a simultaneous predetermined movement of the valve disks 14-16 to obtain a particular result. For instance a free air passage is obtained from pipe 13 to pipe 21 when three operations have been made by plunger 4 and two by plunger 6 as obtained by the depressions in the ramp and by the holding ratchets 14^a-16^a. If, however, a greater or less number of steps have been consummated by the plunger 4, when two were made by plunger 6, it is apparent that this passage would be stopped by disk 16. The same conditions also apply to the passage between pipe 13 and pipe 22. If one of the disks makes a greater number of stops than is necessary with the result that it travels beyond the port opening, it may be released by the holding ratchet and stepped forward again to the extent required. This latter arrange-

ment is particularly useful where more than two valve disks are used. The safety of this arrangement is due to the fact that obstacles at the side of the track cannot operate the plungers in the predetermined order obtained by the ramps for a signal.

The tubes 21 and 22 conduct the air pressure to the cylinders 31 and 32 supported by the frame 30 secured to locomotive cab. The air pressure in these cylinders operates the pistons 33 and 34 connected to the crank 35, pivoted at 36. On the same axis and moving with said crank is the indicator pointer 37 moving on the dial 38-38^a, each side designating by a color or letter, 75 high or low speed. This crank also through rod 39 and connection 40 operates the throttle valve 41 and through rod 42 and connection 43 operates valve 44 on the brake pipe, thus shutting off the power and applying the brakes when one cylinder is operated, or releasing the power and the brakes when the other cylinder is operated.

In the application shown in Fig. 8, where the rails are indicated by 45 and 46, one ramp by A and another by B, it is required that trains pass over drawbridge D at a low speed, the combination caused by ramp A will set the adjustable apparatus which comprises the disks 14 and 16 so as to cause a slow indication and reduce the speed, and the combination on ramp B will set the disks 14 and 16 to cause a high speed indication. In some cases it may be desirable to cause a different indication on one train from that on another, as for instance, it may be necessary to stop a high speed passenger train and only reduce speed on a heavy freight train for the same conditions of track. This can be secured by adding another ridge to ramps A and B and providing a corresponding additional rod on the adjustable apparatus of one of the trains. The adjustable apparatus, therefore, with rods to engage ridges 25, 26 and 27 may be arranged to cause a slow speed and the said apparatus with rods to engage ridges 24, 25, 26 and 27 may be arranged to provide a positive stop.

The application in Fig. 9 shows conditions changeable; *i. e.* as when the switch is set up for a slow speed or for high speed, these conditions being provided by changing the active ramp in correspondence with the condition of the track. The rails 45 and 46 are of the straight track and 45^a-46^a are the rails of the side track. The ramps A and B are brought into active position by magnets 51 and 52 respectively depending on the position of the switch. The plunger 51^a-52^a raising the ramps to the active position when these magnets are energized. Magnet 52 is controlled by wire *x* to battery 54, contact 53^b and wire *z*. When the switch is open to the side track magnet 51 is controlled by wire *y*, battery 54, contact 53^a 130

and wire α . Contacts 53^a and 53^b are operated by rod 53, which moves in conjunction with the switch rails. Thus ramp B, which will cause a high speed indication is in the 5 engaging position when the track is straight and ramp A, which is for slow speed indication is in the engaging position when the switch is set for the side track.

This arrangement indicates the elements 10 of my invention which it is apparent may be applied in a safe and reliable manner to produce a great variety of indications and these indications may be adapted to the varying conditions of traffic.

15 The number of indications may be increased by increasing the number of combinations, which, can be done, first: by increasing the number of the depressions in the ramp, second: by varying the arrangement 20 of the depressions; third: by increasing the number of ridges and corresponding parts, and fourth: by a combination of these elements.

25 This device generates the energy for operating the indicator when the train is passing over the ramp; there is, therefore, no latent energy to cause false operation and it is almost impossible for proper combination to be accidentally set up to operate the 30 indicator.

35 Another way of obtaining a group selection that is particularly adaptable when more than two ratchet wheels are used, is to step up one wheel and then step up the next wheel and release the first, then step up the third wheel and then the first again, which will produce the proper combination for a given signal.

40 It is understood my invention is not limited to the details here shown but may be applied in various ways without departing from the spirit of the invention.

Having described my invention and shown 45 a method of its application I claim as new and desire to secure Letters Patent for the following:

1. The combination of a vehicle having power-controlling and speed-retarding mechanism; power means carried on said 50 vehicle and arranged to actuate said mechanism; an adjustable apparatus interposed between said power means and said mechanism to determine which of said mechanisms is to be affected by said power means; and 55 a plurality of devices disposed in separated relation in the path of said vehicle to operate said apparatus.

2. The combination of a vehicle having power-controlling and speed-retarding 60 mechanisms; power means carried on said vehicle and arranged to actuate said mechanisms; an adjustable apparatus interposed between said power means and said mechanisms to determine which of said mechanisms 65 is to be affected by said power means;

a plurality of devices disposed in grouped arrangement in the path of said vehicle, said devices being adapted each to operatively engage said apparatus to actuate the same in accordance with its character; and 70 means manually operable for selectively arranging said devices to operate said apparatus.

3. The combination of a vehicle having power-controlling and speed-retarding 75 mechanisms; power means carried on said vehicle and arranged to actuate said mechanisms; an adjustable apparatus interposed between said power means and said mechanisms to determine which of said mechanisms 80 is to be affected by said power means; and a plurality of actuating plates disposed in the path of said vehicle, said plates being variously shaped to produce corresponding results in said apparatus. 85

4. The combination of a vehicle having power-controlling and speed-retarding mechanisms; power means carried on said vehicle and arranged to actuate said mechanisms; an adjustable apparatus interposed 90 between said power means and said mechanisms to determine which of said mechanisms is to be affected by said power means; and a plurality of actuating plates disposed in the path of said apparatus to operate the 95 same in a manner corresponding with each plate.

5. The combination of a vehicle having power-controlling and speed-retarding mechanisms; an air compressor having a rod 100 operable from the roadbed; a power transmission operatively connecting said mechanisms and said air compressor, said transmission embodying a single main; a plurality of branch ducts; and means operatively 105 connected with said branch air ducts for reversely affecting said supplying and retarding mechanisms; a permutation valve interposed between said main and branch ducts and embodying a plurality of ported members 110 movable to register with said ducts; an operating mechanism for said ported members, embodying rods extending adjacent to and operable from the roadbed; and a plurality of actuating plates disposed in the 115 path of said rods to move the same in a manner corresponding with each of said plates.

6. A railway signal system comprising a plurality of power-driven vehicles; a plurality of power-controlling mechanisms, one mounted on each of said vehicles and embodying an expansive fluid power supply; a plurality of ported members operatively mounted to control said supply; and an actuating mechanism for shifting said ported members, embodying grouped extensions 125 and actuating plates disposed to engage said extensions, said plates having combination-effecting variations. 130

7. The combination of a vehicle having a power controlling mechanism, said mechanism embodying power means and a speed retarding mechanism; means carried on said vehicle and arranged to actuate said mechanisms; an adjustable apparatus interposed between said power means and said mechanisms for determining which of said mechanisms is to be affected by said power means; and a plurality of devices disposed in spaced relation in the path of said vehicle and of said adjustable apparatus, said devices being shaped to a variety of forms for producing a variety of effects in the time and relation 15 of operation of the parts of said adjustable apparatus.
8. The combination of a vehicle having a power controlling mechanism, and a speed retarding mechanism, power means carried 20 on said vehicle for actuating said mechanisms in predetermined order of time; an adjustable apparatus interposed between said power means and said mechanisms for determining which of said mechanisms is to be affected by said power means, said apparatus embodying a plurality of conduits, each being in open communication with one of said mechanisms; a plurality of movable members having passages disposed therein 25 to establish communication between said power means and either of said mechanisms in accordance with the adjustment of said adjustable mechanism; and a plurality of ramps disposed in the path of said adjustable mechanism for affecting the members thereof successively.
9. The combination of a vehicle having a power controlling mechanism, and a speed retarding mechanism; power means carried 30 on said vehicle for actuating said mechanisms in predetermined order of time; an adjustable apparatus interposed between said power means and said mechanisms for determining which of said mechanisms is to be affected by said power means, said apparatus embodying a plurality of conduits, each being in open communication with one of said mechanisms; a plurality of movable members having passages disposed therein to 35 establish communication between said power means and either of said mechanisms in accordance with the adjustment of said adjustable mechanism; and a plurality of ramps disposed in the path of said adjustable mechanism for affecting the members thereof successively, said ramps having means for operating said power means.
10. In an apparatus as characterized; an adjustable mechanism having a central stationary portion provided with delivery ducts therethrough; a plurality of rotary members juxtaposed to the ends of said stationary portion, one of said rotary members having a diagonal passage and a straight passage 40 formed therethrough for communicating with said delivery passages in said stationary portion, and a second rotary member having a straight passage formed therein for communicating with said delivery passage; and means operable from the roadbed 70 for operating said rotary members for registering one of said passages in each of said rotary members with one or other of said delivery passages.
11. In an apparatus as characterized; an adjustable mechanism having a central stationary portion provided with delivery ducts therethrough; a plurality of rotary members juxtaposed to the ends of said stationary portion, one of said rotary members having a diagonal passage and a straight passage 45 formed therethrough for communicating with said delivery passages in said stationary portion, and a second rotary member having a straight passage formed therein for communicating with said delivery passage; means operable from the roadbed for operating said rotary members for registering one of said passages in each of said rotary members with one or other of said delivery 80 passages; means for holding said rotary members in adjusted position; and means for releasing said rotary members.
12. The combination of a moving railway vehicle; apparatus carried on said vehicle having a plurality of movable members; a vehicle controlling mechanism; controlling means on the track; and a plurality of means carried by said vehicle responsive substantially at the same time to said track means 95 for operating said movable members, thereby actuating said vehicle controlling mechanism.
13. The combination of a railway track; a vehicle moving thereon; apparatus carried on said vehicle having a plurality of movable members; a train controlling mechanism; a plurality of controlling means on the track having particular characteristics with reference to the condition of the track; and a plurality of means carried by said vehicle controlled by said track means for operating said movable members thereby controlling the vehicle in accordance with 105 said track conditions.
14. The combination of a moving railway vehicle; an apparatus carried on said vehicle having a plurality of conductors therethrough, and a plurality of movable members, said conductors interrupted by said 110 movable members except when in a predetermined position; means on the track; and means carried by the vehicle controlled by said track means whereby the continuity of one of said conductors is established.
15. The combination of a railway track; a vehicle moving thereon; an apparatus carried on said vehicle having a plurality of conductors therethrough, and a plurality of movable members, said conductors inter- 125 130

rupted by said movable members except when in a predetermined position; controlling means on the track having particular characteristics; and means carried by the vehicle controlled by said track means whereby the continuity of a particular conductor is established in response to a particular characteristic.

16. The combination of a moving railway vehicle; an apparatus carried on said vehicle having a plurality of movable members; means on the track; and a plurality of oper-

ating members carried by said vehicle controlled by said track means for operating said movable members accumulatively, the 15 accumulative effect from one operating member being retained by the active operation of another of said operating members.

In testimony whereof I affix my signature in the presence of two witnesses.
